UNITED STATES PATENT OFFICE.

WILLIAM J. ENGLISH, OF COHOES, NEW YORK.

TENSION-GUIDE AND THREAD-CLEANER.

No. 895,354.

Specification of Letters Patent. Patented Aug. 4, 1908.

Application filed January 25, 1908. Serial No. 412,601.

To all whom it may concern:

Be it known that I, WILLIAM J. ENGLISH, a citizen of the United States, and a resident of Cohoes, in the county of Albany and State of New York, have invented a new and useful Improvement in Tension-Guides and Thread-Cleaners, of which the following is a full, clear, and exact description.

The purpose of the invention is to provide a continuous tension guide and thread cleaner, which will most effectually split lumps, mites, and other protuberances from the thread in its passage from a bobbin to a reel, free acting and opposing permanent magnetic strippers being provided for the purpose, between which the thread passes, which strippers are loosely mounted in a suitable frame and applicable to any form of winder or reel.

The invention consists in the novel construction and combination of the several parts as will be hereinafter fully set forth and pointed out in the claims.

Reference is to be had to the accompanying drawings forming a part of this specification, in which similar characters of reference indicate corresponding parts in all the figures.

Figure 1 is a side elevation of the frame shown as supporting a reel and bobbin, and the improved tension guide and cleaner, and as provided with a driving mechanism for the shaft on which the reel is mounted; Fig. 2 is a vertical longitudinal section through the device; Fig. 3 is a front elevation of the same; and Fig. 4 is a plan view thereof.

The frame A may be of any desired construction. That shown consists of rear uprights 10, forward uprights 10^a supported by 40 suitably located transverse beams, and in addition to the aforesaid parts, the said frame consists of lower side beams 11 that extend beyond the front of the frame, upper side beams 11^a, and intermediate side beams 12 45 that also extend beyond the front of the frame. The intermediate side beams 12 are connected by a cross bar 13 at their forward ends, and a similar cross bar 14 connects the outer ends of lower side beams 11. A shaft 50 15 is mounted in suitable bearings located on the upper cross bars 11^a, and this shaft carries a pulley 16 that is connected with a belt 17, which belt passes over a driving pulley 18 on the drive shaft 19, journaled in the frame 55 and driven from any suitable source of power.

The reels 20 are located on the upper shaft 15 and the bobbins 21 are located on the lower cross bar 14, while the tension guide and thread cleaning device or devices are adjustably secured to the cross bar or beam 13 carried by the intermediate beams 12, as is clearly shown in Fig. 1. The holder or casing B of the device is made in two sections, b and b', each section consisting of an upright 65 23 that is attached at its lower portion to the side faces of the base 22. At the upper portion of the forward face of each upright 13, a guard flange 24 is located, and these flanges extend in direction of each other, as is best 70 shown in Fig. 3, and also extend from the upper edges of the said uprights 23 downward to a point near their centers, and the forward faces of the said guard flanges 24 are beveled in direction of the space between them, as is illustrated at 25 in Fig. 4. Shorter 75 guard flanges 26 are formed at the inner edges of the uprights 23 at their bottom portion, and these lower flanges 26 have integral with their bottom portion, floor sections 26^a, 80 as is illustrated in Fig. 2.

The upper edges of the lower guard flanges 26 are beveled at the front upwardly, as is shown at 27 in Fig. 3, and the lower edges of the guard flanges 24 are beveled in a downward direction. Thus it will be observed that at the front of the holder or casing B constituting the device, a space or opening 85 is provided, defined by the lower edges of the upper guard flanges 24, and the upper edges 90 of the lower guard flanges 26, and the inner edges of the standards 23 at their central portions.

At the central rear portion of each upright 23, an offset 29 is produced, as is best shown 95 in Fig. 2, and guard flanges 30 extend from this offset in direction of each other, and the said guard flanges 30 are opposite the space between the upper and lower guard flanges 24 at the front, as is also shown in Fig. 2. A 100 suitable space intervenes the guard flanges 30, the space being practically of the same width as that between the guard flanges 24 and 26, and the outer faces of the guard flanges 30 are beveled in the direction of the 105 space between them, as is shown at 31 in Fig. 4.

An ear 32 is carried from the base 22 at that side opposite which the holder or casing is secured, and this lug 32 is pivotally connected with a member 33 of a bracket 34 adapted to be attached in any suitable or 110

approved manner to the intermediate front cross bar or beam 13. The pivotal connection between the bracket 33 and the lug 32 of the base 22 is through the medium of a set 5 screw 35, so that the holder or casing can be adjusted relatively to the bobbin 21 and the reel 20 to which the thread is to be passed, and be secured in its adjusted position. The thread 36 passes from the bobbin 21 over the 10 customary wire guide 37 and is then carried through the said holder between its members and likewise between two strippers C and C' that are located opposite each other, and loosely in the said holder or casing, the lower 15 ends of the strippers resting upon the floor sections 26^a, and the space between these strippers C and C' when the strippers are forced apart will be sufficient to permit the passage of the thread. These strippers C 20 and C' are magnetized or are permanent magnets, so that one will attract the other, and consequently the said strippers will accommodate themselves to thread of different diameters, and in hugging the thread closely 25 will remove therefrom any lumps, motes, or any other protuberances to be found on the thread as it passes from a bobbin 21 to the reel 20.

This device is exceedingly simple, and is 30 effective in its operation, the magnetic strippers C and C' being at all times ready for action, and these strippers may be removed and replaced any time.

Having thus described my invention, I

claim as new and desire to secure by Letters 35 Patent, —

1. A tension guide and cleaner for thread, consisting of a holder, and magnetized strippers oppositely and loosely mounted therein. 40
2. A tension guide and cleaner for thread, consisting of a holder, and positive magnets oppositely and loosely located in said holder, adapted to receive the thread between them. 45
3. A tension guide and cleaner for thread, consisting of a holder, magnetized strippers oppositely and loosely mounted in the holder, a base for the holder, a bracket and an adjustable connection between the said base and the bracket. 50
4. A tension guide and cleaner for thread, consisting of a holder, comprising two upright sections provided with a connecting base, said sections being spaced apart, the said sections at their inner edges being provided with upper and lower spaced and opposed guard flanges at one side, and a bottom section and opposing spaced guard flanges at the central portion of the other side, opposing magnetic strippers loosely mounted in the holder, and means for adjustably attaching the holder to the support. 55 60

In testimony whereof I have signed my name to this specification in the presence of two subscribing witnesses.

WILLIAM J. ENGLISH.
